FRANKFURTER GRILL

John J. Connolly, Pelham Manor, N. Y.

Application January 28, 1957, Serial No. 44,634

Term of patent 14 years

(Cl. D81—10)

FIG. 1.

FIG. 2.

FIG. 3.

The rear view of the grill is identical to the front view, as shown in Figure 2, with the exception that there is no outwardly projecting control unit at the rear.

I claim:

The ornamental design for a frankfurter grill, as shown and described.
